S. D. SEMENOW AND H. L. ABRAMOVITZ,
TAP FOR BARRELS, DRUMS, OR RECEPTACLES CONTAINING GASOLENE.
APPLICATION FILED JULY 17, 1917.

1,304,390.

Patented May 20, 1919.

UNITED STATES PATENT OFFICE.

SAUL D. SEMENOW AND HYMAN L. ABRAMOVITZ, OF PITTSBURGH, PENNSYLVANIA.

TAP FOR BARRELS, DRUMS, OR RECEPTACLES CONTAINING GASOLENE.

1,304,390.

Specification of Letters Patent. Patented May 20, 1919.

Application filed July 17, 1917. Serial No. 180,972.

To all whom it may concern:

Be it known that we, SAUL D. SEMENOW and HYMAN L. ABRAMOVITZ, citizens of the United States of America, residing at Pittsburgh, county of Allegheny, and State of Pennsylvania, have invented certain new and useful Improvements in Taps for Barrels, Drums, or Receptacles Containing Gasolene, of which the following is a specification.

10 This invention relates to taps for barrels, drums, and other receptacles designed to contain gaseous or vaporous fluids, as for example, gasolene.

The prime object of the invention is to 15 provide a simple and efficient device of the character mentioned designed to prevent the waste of the vapors or fluid when tapping the contents of the receptacle.

A further object of the invention is to provide 20 a device of such class, in a manner as hereinafter set forth, for supplying air to the receptacle when occasion so requires, to facilitate the discharge of gasolene.

Further objects of the invention are to 25 provide a tap of the class referred to, which is simple in its construction and arrangement, strong, durable, thoroughly efficient, conveniently adjusted and comparatively inexpensive to manufacture.

30 With the foregoing and other objects in view, the invention consists of the novel construction, combination and arrangement of parts, as hereinafter referred to, wherein is shown an embodiment of the invention, 35 but it is to be understood that changes, variations and modifications can be resorted to which fall within the scope of the claims hereunto appended.

In the drawings wherein like reference 40 characters denote corresponding parts throughout the several views:

Figure 1 is a part elevational and a part vertical sectional view of a tap device constructed in accordance with this invention;

45 Fig. 2, a detail vertical sectional view particularly showing the bung element of the tap;

Fig. 3, a view similar to Fig. 2 particularly showing the plug of the bung element 50 adjusted; and

Fig. 4, a part elevational and a part sectional view of the tap device in operative position, certain of the elements being omitted.

55 A tap in accordance with this invention,

comprises a bung element, an air supply element and a discharge element.

The head of the barrel, drum or receptacle, hereinafter termed barrel, is indicated at 1, and which is provided with a bung 60 hole 2, having the wall thereof threaded.

The bung element consists of a disk 3, having a centrally disposed opening 4, with the wall thereof threaded. The disk 3, has peripheral threads 5, which have threaded 65 engagement with the threads of the wall of the opening 2, for securing the disk in the opening for the purpose of closing the latter. Disk 3, as shown, is also provided with a port 6, said port leading from its inner face 70 to the opening 4, the purpose of which is to form a communication between the vent pipe 10 and a tubular member 20 extending downwardly through the device, whereby air, when required, may be supplied to the 75 interior of the receptacle. In some cases, however, as hereinafter referred to, the port 6 and vent pipe 10 may be omitted.

The reference character 7, denotes a peripherally threaded plug which engages with 80 the threads of the wall of the opening 4, for the purpose of normally closing said opening 4, and port 6. The plug 7, is adjustable, and has its lower end reduced as at 8, and which is adapted, when the plug 7 is adjusted 85 inwardly, to engage a stop member 9, whereby the inward movement of the plug 7 will be arrested.

Depending from the disk 3, is a vent pipe 10, having its lower end in the form of an 90 L, as at 11 and its upper end funnel-shaped, as at 12, and which is secured to the inner face of the disk 3, as at 13. The stop arm 9, is arranged within the funnel-shaped portion 12, as well as, being secured therewith, 95 at a point in the line of inward travel of the plug 7.

The upper face of the plug 7 is grooved as at 14, for the purpose of receiving the end of a suitable instrument or tool, herein- 100 after referred to, to adjust the plug 7.

The upper face of the disk 3, has formed integral therewith a pair of upwardly extending studs 15, and each of which is formed with an opening 16. The function 105 of the studs 15 will be presently referred to.

The bung element further includes a flanged closure cap 17, having pockets 18, for the reception of the studs 15, when the cap 17 extends within and has threaded en- 110

gagement with the threads of the opening 2, as shown in Fig. 2.

The disk 3 is of less thickness than the depth of opening 2, and by such an arrangement, when the disk 3 is mounted in position to close the opening 2, as illustrated in Fig. 2, the cap 17 can extend in said opening and engage with the threads of the wall thereof. Interposed between the flange 10 of the cap 17, and the head 1 is a gasket 19.

20 designates a tube preferably peripherally threaded, as shown, extending downwardly through the device and adapted to have its lower end connected with the bung element. Said tube is designed for the purpose of supplying air to the interior of the receptacle when required and also for the purpose of connecting or coupling the bung element to the tap device proper or to the 25 discharge element thereof, as hereinafter referred to. 21 designates a spider located at the outer or upper end of the tube 20. Extending down through the tube 20, is an adjusting tool 22, for the plug 7. Said tool 25, has its lower end widened and flattened, as at 23, for engagement with the groove 14, as shown in Fig. 1, for the purpose of adjusting plug 7. The outer end of the tool 22 has a handle 24.

30 The discharge element comprises an elbow coupling 25, provided with an outwardly extending interiorly threaded nipple 26, which opens into the coupling 25. The tube 20 extends through the nipple 26, elbow 25, and has a threaded engagement with the threads of the nipple 26.

Detachably connected to the upper end of the coupling 25 is a pipe line 27 provided with a faucet or discharge valve 28.

40 Detachably connected to the lower end of the coupling 25, is a hollow cylindrical member 29, provided at its inner portion with peripheral threads 30. At the inner end of the member 29, an inwardly extending annular flange 31 is provided, having diametrically opposed openings 32. The member 29, in proximity to the flange 31 is formed with diametrically opposed outlet slots 33.

50 The flange 31 forms a clearance or opening 34, for the passage of the tube 20, for a purpose to be presently referred to.

The openings 32 are adapted to receive the studs 15 of the bung element when the 55 discharge element or the tap device proper is applied to the bung element.

The studs 15 extend through the openings 32 and as illustrated, pins 35 may be passed through the openings 16 of the studs 15, 60 thus connecting the discharge element and the bung element together. The discharge element and the bung element, however, may be connected or coupled together by the tube 20 without the employment of the 65 pins 35. This latter connection may be

made by entering the lower threaded end of the tube 20 in the threaded opening 4 of the bung element 3 after the plug 7 has been adjusted downwardly sufficiently to allow the threads of tube 20 to engage 70 threads of the openings 4.

The bung element is adjusted inwardly by a rotative movement imparted to the discharge element or by turning the tap device proper, it being understood that when the 75 member 29 is in the position shown by Fig. 1, the studs 15 of the bung element will be entered in the openings 32 of the flange of element 29; therefore, a bodily rotation of the element 29 will cause the bung element 80 to move in unison therewith, whereby the parts may be moved into the position shown by Fig. 4.

In some cases, particularly where the receptacle contains high gravity gasoline, it 85 is unnecessary to introduce air to the interior of the container in order to discharge the contents; consequently, the air supplying means may be omitted.

Assuming that the vent pipe 10 and the 90 adjustable plug 7 are employed, Fig. 2 shows the relative position of the parts for shipping the container. To discharge the contents, cap 17 is removed, after which the assembled tap device is applied to the 95 bung element with studs 15 of the bung entered in the openings 31 of the member 29 and the threaded portion 30 of said member engaging the threaded wall of opening 2 of the container. Plug 7 is then adjusted 100 inwardly sufficiently to permit member 20 to engage the threaded wall of the opening 4, thereby connecting or coupling the discharge and bung elements together. A rotation of the discharge element will advance 105 the bung element and the lower end of the discharge element into the container, thereby bringing the outlet slots 33 below the head 1, and forming a communication between the interior of the container and the 110 discharge element. The container or barrel is then inverted, and valve 28 of the pipe line opened, thereby forming an open passage for vapors and liquids from the interior of the barrel to the pipe 27, through 115 slots 33 and element 29.

In the event that it is necessary to admit air to the interior of the container for the purpose of discharging its contents, plug 7 is moved inwardly by tool 22 a distance sufficiently to uncover port 6 of bung element 3, thereby permitting air to reach the interior of the container through pipe 20 and vent pipe 10.

The manner of setting up the tap when 125 opening the bung hole of the barrel will prevent any possibility of waste during the tapping operation.

What we claim is:

1. In a tap of the character described, an 130

adjustable bung element, an adjustable discharge element, one of said elements having a projection and the other an opening to receive the projection, and an element extending through the discharge element for coupling the bung element to the discharge element.

2. In a tap of the character described, an adjustable internally threaded bung element, 10 an adjustable discharge element, one of said elements having a projection and the other an opening to receive the projection, and means extending through the discharge element for coupling the bung element to the 15 discharge element, said coupling means having external threads to engage the threads of the bung element.

3. The combination with a container having a bung-hole with the wall thereof 20 threaded, of a tap including a threaded bung element entered in the bung-hole and adapted to be passed to the interior of the container, a tubular discharge element having an outlet slot in the wall thereof and having 25 threads to engage the bung-hole wall, coaxing engaging means on the bung and discharge elements, and means for coupling the discharge element and bung element together including an element extending 30 through the discharge element and engaging the bung element.

4. In combination with a container having a bung-hole with the wall thereof threaded, of a tap including a threaded bung element 35 entered in the bung-hole and adapted to be passed to the interior of the container, said bung element being interiorly threaded, a hollow discharge element having an outlet slot in the wall thereof and having threads 40 to engage the bung-hole wall, one of said elements having a projection and the other an opening to receive the projection, and means for coupling the discharge element and the bung element together, said means including 45 an element extending through the discharge element and having threads to engage the internally threaded portion of the bung element.

5. In a tap of the character described, an 50 adjustable ported bung element having means for controlling the passage of air through the port, a vent pipe, a tube connected with the bung element and in communication with the vent pipe through the 55 port of the bung element, and a discharge element connected with the bung element.

6. In a tap of the character described, an

adjustable bung element having a normally closed air supply port, a discharge element adapted to be connected with the bung element and provided with outlet slots, means for normally closing the port of the bung element, a tube extending through the discharge element and connected with the bung element, and means for operating the closure 60 means for said port to open the latter.

7. In a tap of the character described, an adjustable ported bung element including an apertured disk and a plug in said disk for controlling the port, a vent pipe, a tube associated with said bung element, means for operating said plug to open the port, and a discharge element surrounding the tube and detachably connected with the bung element.

8. In a tap of the character described, a 75 ported bung element including an apertured disk, a plug in the bung element controlling the port thereof, a vent pipe secured to the bung element, a tube associated with the bung element, means for operating said plug 80 to open said port, and a discharge element surrounding the tube and adapted to be detachably connected with the bung element, said discharge element provided with outlet slots at its inner end.

9. In a tap of the character described, an adjustable ported bung element having means for controlling the passage of air through the port, a vent pipe, a tube connected with the bung element and in communication with the vent pipe through the 90 port of the bung element, and a discharge element surrounding said air supply element and adapted to be connected with the bung element.

10. A tap for the purpose set forth, comprising a bung element consisting of an adjustably threaded disk having connected to the inner face thereof a vent pipe, said disk having a central opening with the wall thereof threaded and further having an air supply port extending from its inner face to said opening, an adjustable plug having threaded engagement with the wall of said opening for normally closing said port, and 100 a pair of studs projecting from the outer face of said disk.

In testimony whereof we affix our signatures in the presence of two witnesses.
